UNITED STATES PATENT OFFICE.

RUDOLPH STEINERT, OF NEW HAVEN, CONNECTICUT.

PHONOGRAPH-NEEDLE AND RESONATOR THEREFOR.

1,391,425.

Specification of Letters Patent. Patented Sept. 20, 1921.

Application filed October 25, 1919. Serial No. 333,286.

To all whom it may concern:

Be it known that I, RUDOLPH STEINERT, a citizen of the United States, residing at New Haven, in the county of New Haven 5 and State of Connecticut, have invented new and useful Improvements in Phonograph-Needles and Resonators Therefor, of which the following is a specification.

The present invention relates to phonograph needles and resonators therefor, and has for its object to provide an improved resonator which will increase and clarify the reproduction; eliminate the metallic quality noticeable in some reproducing devices now 10 in use, and in which the amplified tone will be of purer quality and the disagreeable crepitations so often found in using the ordinary needle, and which materially detract from the proper rendition of music, are 15 practically done away with or so modified as to eliminate any disagreeable results.

A further object of my invention is to so arrange the resonator relative to the stylus as that it is held in proper position with 20 respect to the inclined needle, so that it may be utilized with reproducing mechanisms now in use without the need of specially designed parts.

I accomplish the objects aimed at by providing a resonator, preferably formed as a thin metal shell, so shaped and disposed with 25 respect to the stylus as that it gives the greatest amplitude of sound and clearness in reproduction, without in any way interfering with the tracking of the point over the record or with the insertion of the needle in the holder of the usual reproducing apparatus to which it is applied.

In order that the invention may be clear 30 to those skilled in the art, I have, in the accompanying drawings, shown two embodiments of my invention, but these embodiments are, it is to be noted, illustrative and in no sense restrictive, as the invention may 35 be embodied in other physical forms without departing from my invention.

In the drawings:—

Figure 1 is a view in side elevation of a resonator and needle made in accordance 40 with my invention, the reproducing apparatus being conventionally shown.

Fig. 2 is a sectional view of the resonator and needle.

Fig. 3 is an end view looking from the 45 left in Fig. 1.

Fig. 4 is a bottom plan view.

Fig. 5 is a view of a reproducing apparatus conventionally shown, with the resonator attached to the needle holder.

Referring to the drawings by numbers, 50 like numbers indicating like parts in the several views, 10 indicates the needle, which is made up of the stylus 11, of any desired type or form, and the resonator 12, which, as shown, consists of the bell-shaped or 55 dome-like hood 13, preferably, as shown in Fig. 4, of general elliptical form in plan, and having its lower edge 14 flared outwardly from the hood or dome 13.

The stylus 11 passes through the top of 70 the dome 13 in an inclined direction and in line with the major longitudinal axis of the resonator, so as to bring the active point of the stylus substantially centrally of the mouth of the resonator and projecting below 75 the lower flared edge 14 thereof a sufficient distance to permit the point of the stylus 11 to engage the groove in the record, and, when the needle is in the socket of the needle holder, to maintain the lower edge of the 80 resonator close and parallel to the plane of the surface of the record. The needle 11 will be fixed in any suitable manner, as by compression of the resonator about it so as to maintain the parts in a state of relative 85 rigidity.

It will be observed that the dome 13 is 90 asymmetrical or distorted relative to the bell mouth, being preferably inclined from the perpendicular in the line of the major longitudinal axis of the elliptical mouth so as to throw the top of the dome to one side of a line perpendicular to the base. This gives a structure in which needle-inclination 95 necessary for fixing the needle in the usual reproducer is secured, and at the same time a central positioning of the point of the stylus relative to the mouth of the resonator is maintained.

Arranged in this manner, the needle is 100 free to vibrate under the irregularities of the groove, and the vibrations are, according to my present theory, concentrated and condensed by the resonator and transmitted to the needle in full amplitude, so as to clarify 105 and intensify the sound and eliminate the false tones which result from the use of a bare needle.

The dome-like resonator with its flared sound-collecting edge is, it will be observed, 110 in rigid relation to the needle, both in the form of the invention just described, and in

that modification shown in Fig. 5, presently to be described, so that vibrations are, by such resonator element, transmitted to the needle at a point between its ends, and by 5 it in turn transmitted to the reproducer.

In Fig. 5 of the drawings, the invention is adapted to the use of the ordinary commercial needle by securing the resonator 12 directly to the needle holder 16 of the reproducer; so that the ordinary commercial needle, when inserted in the socket and clamped by its holding screws, will give a record engaging stylus with the resonator and needle in the same relative positions as 15 in the case where the stylus and resonator are secured together, as shown and described.

It will be understood, of course, that such changes as are within the scope of mechanical skill may be made without departing from 20 the spirit of my invention.

I claim:—

1. In a device of the class described, the combination of a hollow, substantially dome-shaped member; and a needle passing 25 through the top of and traversing said member in a direction inclined to the perpendicular.

2. In a device of the class described, the combination of a hollow, dome-shaped member; and a needle passing through the top of said member and in a direction inclined 30 to the perpendicular.

3. In a device of the class described, the combination of a hollow, dome-shaped member the top of which is distorted from the 35 perpendicular; and a needle passing through

the top of and traversing said member in a direction inclined to the perpendicular.

4. A stylus for phonographs comprising a hollow, dome-shaped resonator, the top of 40 which is distorted from the perpendicular; and a needle passing through the distorted top of and fixed in said resonator on a line inclined to the perpendicular.

5. A stylus for phonographs comprising 45 a hollow, dome-shaped member having an open lower end; and a needle passing through the top of and traversing said member in a direction inclined to the perpendicular and with its record-engaging end disposed substantially centrally of said open 50 lower end.

6. A stylus for phonographs comprising a hollow, dome-shaped member having a substantially elliptical, open, lower end; and a 55 needle passing through the top of and traversing said member in a direction inclined to the perpendicular and with its record-engaging end disposed substantially centrally of said open 60 lower end.

7. A stylus for phonographs comprising a hollow, dome-shaped member having its top distorted from the perpendicular and a substantially elliptical, open, lower end; and a needle passing through the top of said member in a direction inclined to the perpendicular and with its record-engaging end disposed substantially centrally of said open 65 lower end.

In testimony whereof I have hereunto set 70 my hand.

RUDOLPH STEINERT.
